United States Patent Office

Des. 182,940

Patented May 27, 1958

182,940

BOTTLE POURER FOR LIQUIDS

William D. Williams, Toledo, Ohio, assignor, by mesne assignments, to National Laboratories, Inc., a corporation of Delaware

Application June 19, 1957, Serial No. 46,652

Term of patent 14 years

(Cl. D58—26)

Fig. 1

Fig. 2

Figure 1 is a rear perspective view of the bottle pourer for liquids showing my new design;

Figure 2 is a top plan view of the pourer; and

Figure 3 is a side elevation of the pourer.

I claim:

The ornamental design for a bottle pourer for liquids, as shown.
